P. W. BLACK

DEVICE FOR DISPENSING AND MOISTENING GUMMED TAPE

Filed April 29, 1924

FIG. 1.

FIG. 2.

UNITED STATES PATENT OFFICE.

PAUL W. BLACK, OF SAN FRANCISCO, CALIFORNIA.

DEVICE FOR DISPENSING AND MOISTENING GUMMED TAPE.

Application filed April 29, 1924. Serial No. 709,807.

To all whom it may concern:

Be it known that I, PAUL W. BLACK, a citizen of the United States, and a resident of the city and county of San Francisco, State of California, have invented a certain new and useful Device for Dispensing and Moistening Gummed Tape, of which the following is a specification.

The invention relates to a device for dispensing and moistening gummed tape which

10 is used for sealing packages and cartons and for mending purposes.

An object of the invention is to provide a gummed tape dispensing and moistening device which may be carried in the pocket.

15 Another object of the invention is to provide a gummed tape moistening device with means for sealing the moistening chamber when the device is not in use.

20 Another object of the invention is to provide an efficient and inexpensive gummed tape moistening device in which the tape is moistened after it has passed the cutting edge, so that when the tape is severed at 25 the cutting edge, the remaining portion of the edge is still dry.

Another object of the invention is to provide a gummed tape moistening device with means for mixing the applied moisture with 30 the gum, so that the gummed surface immediately becomes sticky.

The invention possesses other advantageous features, some of which, with the foregoing, will be set forth at length in the following description, where I shall outline in full that form of the invention which I have selected for illustration in the drawings accompanying and forming part of the present specification. In said drawings I have shown one 40 form of device embodying my invention, but it is to be understood that I do not limit myself to such form, since the invention, as set forth in the claims, may be embodied in a plurality of forms.

45 Referring to said drawings:

Figure 1 is a vertical longitudinal section through the device of my invention with the moistening device cover in position to seal the moistening device chamber.

50 Figure 2 is a top view of the device of my invention, a portion of the roll chamber cover and the moistening device cover being removed to show the construction.

Figure 3 is a cross-section taken on the line 3—3 Figure 1.

Figure 4 is a perspective view of the device with the moistening device cover in closed position.

Figure 5 is a perspective view of a fragment of the extending portion of the 60 cover plate of the roll chamber showing the projections thereon for engagement by the moistening device cover, the moistening device cover being indicated in broken lines.

The device of my invention is constructed 65 to permit it to be carried in the pocket and is provided with means for preventing the water or moisture from leaking therefrom while it is being carried in the pocket. By providing a small, portable device of 70 this character, the user may carry it to the packages to be sealed, thus greatly reducing the labor of sealing packages. Heretofore, devices for moistening gummed tape have been large so that it was necessary to 75 carry the package to the device, an operation which is expensive both in time and effort.

The device of my invention comprises a 80 casing 2 having side walls 3 which enclose two chambers, the chamber 4 being adapted to contain the roll 5 of gummed tape and the chamber 6 containing a moistening device preferably in the form of a charge of absorbent material such as the sponge 7. The 85 two chambers 4 and 6 are separated from each other by the transverse wall 8 which extends upward for the height of the side walls 3. The moistening device chamber 6 is closed at the top by a plate 12 which is 90 preferably hinged at 13 to the upper end of the wall 8. The plate 12 is preferably provided along its side with beveled edges which seat against complementary beveled edges on the inner sides of the side walls 3, 95 so that the plate 12 makes a tight fit with the side walls and is held in place by wedging action. The plate 12 is of less length than the chamber 6 so that an opening is provided between the end of the plate 12 100 and the end wall 14 of the casing, through which the moistening device 7 is exposed. The moistening device preferably extends upward above the plane of the plate 12, so that the tape which is drawn over the plate 12 is brought into contact with the moistening device.

The roll chamber 4 is closed by a cover 15 which is hinged to the back wall 16 of the casing and which is provided with 110

side flanges 17 which form a relatively tight fit with the side walls 3 of the casing. By lifting the cover, the roll chamber is opened to permit the ready insertion of another roll of gummed tape, or labels. The cover 15 is provided with an extending portion 18, which overlies and is spaced from the plate 12, forming with the plate 12 a passage through which the unrolled tape passes and by which the tape is directed to the moistening device. The portion 18 of the cover plate is provided with an aperture 19 to permit the insertion of the finger or thumb for the purpose of advancing the tape. The tape is advanced by the finger until a suitable portion thereof projects beyond the edges 20 of the cover extension 18 and then the projecting portion of the tape is grasped by the fingers and drawn across the moistening device and after sufficient tape has been withdrawn to meet the necessities of the situation, the tape is severed by tearing it along the edge 20.

In order to insure thorough wetting of the gummed surface of the tape, I have arranged a brush 21 in the casing, adjacent to and preferably immediately behind the projecting portion of the sponge 7, so that as the tape is drawn across the moistening device, the gum is first moistened by the sponge and the moisture is then distributed and mixed with the gum by the bristles of the brush, so that it is not necessary to wait for the gum to become sticky before the tape is used. The bristles of the brush, serving to mix the moisture with the gum, cause the gum to immediately become sticky.

Means are provided for closing the moistening device chamber when the device is not in use, to prevent loss of water by evaporation and leakage. Pivoted to the casing adjacent the opening therein through which the moistening device projects, is a hood or cover 22 which is movable to cover and expose the moistening device. The end 14 of the casing is preferably curved and the cover 22 is similarly curved, so that when the cover is moved to expose the moistening device, it lies snugly against the end 14 of the casing, as shown in dotted lines in Figure 1. The cover 22 makes a tight joint with the end 14 of the casing and with the side walls thereof and, when the cover is moved to close the moistening device chamber, the forward edge of the cover forms a tight joint with the plate 12, thereby effectively sealing the moistening device chamber. In order to form a tight joint between the cover 22 and the plate 12, the plate is provided with a transverse groove 23 into which the edge of the cover 22 extends, the inner surface of the cover forming a tight joint with the side of the groove. The cover 22 is provided with a projection 24 which may be engaged by the thumb of

the operator to shift the cover from closed to open position and vice versa.

In order to insure that the cover 15 of the roll chamber 4 will remain in closed position while the device is being carried in the pocket and when it is otherwise not in use, means are provided for locking the cover 15 in position. For this purpose the side flanges 17 of the cover are provided at their ends, which lie adjacent the moistening device aperture, with lips 25 which are disposed at the opposite ends of the groove 23. When the cover 22 is moved to close the moistening device chamber, the forward edge of the cover engages the lip 25 thus holding the cover 15 in position. It is understood that the cover 22 is in relatively tight frictional contact with the casing 2, so that pressure must be exerted against the cover 22 to move it.

Moisture may be added to the absorbent pad 7 by introducing it into the pad through the opening in the chamber 6 and, when it is desired to renew the moistening device pad, the plate 12 may be lifted to provide access to the chamber 6.

By virtue of this invention I have produced a simple, portable gummed tape dispensing and moistening device which may be carried in the pocket of the user and which, when so carried, may be closed to prevent leakage of moisture therefrom.

I claim:

1. A device of the character described comprising a casing having a chamber therein adapted to contain a roll of gummed tape, a bed plate, a cover for the chamber having a portion extending over the bed plate and forming with the plate a passage through which the unrolled tape passes and a moistening device disposed contiguous to the end of the passage so that the tape emerging from the passage contacts with the moistening device.

2. A device of the character described comprising a casing having a chamber therein adapted to contain a roll of gummed tape and having a chamber therein containing a moistening device, a plate partially covering the latter chamber to expose a portion of the moistening device, and a cover for the roll chamber having a portion extending over the plate and forming therewith a passage through which the unrolled tape passes and by which the tape is conducted into contact with the exposed portion of the moistening device.

3. A device of the character described comprising a casing having a chamber therein adapted to contain a roll of gummed tape and having a chamber therein containing a moistening device, a plate partially covering the latter chamber to expose a portion of the moistening device, and a cover for the roll chamber having a portion over-

lying the plate and forming therewith a passage through which the unrolled tape passes and by which the tape is conducted into contact with the exposed portion of the moistening device, said portion of the cover being provided with an aperture to permit contact with the tape for the purpose of advancing it in the passage.

4. A device of the character described comprising a casing having a chamber therein adapted to contain a roll of gummed tape and having a chamber therein containing a moistening device, a plate partially covering the latter chamber to expose a portion of the moistening device, a cover for the roll chamber having a portion overlying the plate and forming therewith a passage through which the unrolled tape passes, said portion terminating short of the edge of the plate and the end of the portion constituting a cutting member for the projected tape.

5. A device of the character described comprising a casing having a chamber therein adapted to contain a roll of gummed tape, a second chamber separated from the roll chamber and having an opening therein, a charge of water absorbent material in the second chamber exposed at said opening and a movable cover for closing said opening.

30 6. A device of the character described comprising a casing having a chamber therein adapted to contain a roll of gummed tape, a second chamber containing a moistening device, a cover for the roll chamber, and a cover for the moistening device adapted to engage said first mentioned cover when the moistening device cover is moved to close the moistening device chamber.

40 7. A device of the character described comprising a casing having a chamber therein adapted to contain a roll of gummed tape, a second chamber separated from the roll chamber and having an opening therein, a charge of water absorbent material in the second chamber exposed at said opening, means for directing the unrolled tape into contact with the exposed portion of the absorbent material and a movable cover for closing said opening.

50 8. A device of the character described comprising a casing having a chamber therein adapted to contain a roll of gummed tape, a second chamber separated from the roll chamber and having an opening therein, a charge of water absorbent material in the second chamber exposed at said opening and a cover pivoted to and forming a tight joint with the casing adapted to be moved to open and close said opening.

60 9. A device of the character described comprising a casing having a chamber therein adapted to contain a roll of gummed tape, a second chamber containing a moistening device, a plate partially covering the second

chamber and partially exposing said moistening device, said plate being provided adjacent its end with a transverse groove and a cover pivoted to the case and adapted to be moved to cover the exposed portion of the moistening device and seat one edge of the cover in the groove.

10. A device of the character described comprising a casing having a chamber therein adapted to contain a roll of gummed tape, a second chamber containing a moistening device, a plate partially covering the second chamber and partially exposing said moistening device, a cover for the roll chamber having a portion overlying said plate and forming therewith a passage through which the unrolled tape passes and a cover for the exposed portion of the moistening device arranged to engage said portion of the roll chamber cover when the moistening device cover is moved to close the moistening device chamber.

11. A device of the character described comprising a casing having a chamber therein adapted to contain a roll of gummed tape and having a chamber therein containing a moistening device, a plate partially covering the latter chamber to expose a portion of the moistening device and a cover for the roll chamber having a portion overlying the plate and forming therewith a passage through which the unrolled tape passes, and the end of the portion constituting a cutting member for the projected tape.

12. A device of the character described comprising a casing having a chamber therein, a charge of absorbent material in said chamber partially exposed through an opening in said chamber, means for directing gummed tape to said exposed material and a brush arranged adjacent the exposed material and adapted to contact with the gummed surface as it is being moistened.

13. A device of the character described comprising a casing having a chamber therein adapted to contain a roll of gummed tape, a bed plate, a cover for the chamber hinged to the casing to permit access to the chamber, an extension on the cover overlying the bed plate and forming with the plate a passage through which the unrolled tape passes and a moistening device disposed contiguous to the end of the passage.

14. A device of the character described comprising a casing having a chamber therein adapted to contain a roll of gummed tape and having a chamber therein containing a moistening device and a bed plate over which the unrolled tape passes hinged to the casing and closing the moistening device chamber.

In testimony whereof, I have hereunto set my hand.

PAUL W. BLACK.
